(57) **CLAIM**

The ornamental design for a privacy screen as shown and described.

DESCRIPTION

FIG. 1 is a front perspective view of a privacy screen showing a first embodiment of our design;

FIG. 2 is a front elevation view of the privacy screen of FIG. 1;

FIG. 3 is a rear elevation view of the privacy screen of FIG. 1;

FIG. 4 is a left-side elevation view of the privacy screen of FIG. 1;

FIG. 5 is a right-side elevation view of the privacy screen of FIG. 1;

FIG. 6 is a top plan view of the privacy screen of FIG. 1; FIG. 7 is a bottom plan view of the privacy screen of FIG. 1;

FIG. 8 is a front perspective view of a privacy screen showing a second embodiment of our design;

FIG. 9 is a front elevation view of the privacy screen of FIG. 8;

FIG. 10 is a rear elevation view of the privacy screen of FIG. 8;

FIG. 11 is a left-side elevation view of the privacy screen of FIG. 8;

FIG. 12 is a right-side elevation view of the privacy screen of FIG. 8;

FIG. 13 is a top plan view of the privacy screen of FIG. 8; FIG. 14 is a bottom plan view of the privacy screen of FIG. 8;

FIG. 15 is a front perspective view of a privacy screen showing a third embodiment of our design;

FIG. 16 is a front elevation view of the privacy screen of FIG. 15;

FIG. 17 is a rear elevation view of the privacy screen of FIG. 15;

FIG. 18 is a left-side elevation view of the privacy screen of FIG. 15;

FIG. 19 is a right-side elevation view of the privacy screen of FIG. 15;

FIG. 20 is a top plan view of the privacy screen of FIG. 15; and,

FIG. 21 is a bottom plan view of the privacy screen of FIG. 15.

The broken lines in FIGS. 8-21 depict portions of the privacy screen that form no part of the claimed design.

1 Claim, 15 Drawing Sheets
